DESIGN FOR A SUIT

Jules Freedman, New York, N. Y., assignor to Morris W. Haft & Bros., Inc., New York, N. Y.

Application May 8, 1948, Serial No. 146,235

Term of patent 3½ years

(Cl. D3—4)

To all whom it may concern:

Be it known that I, Jules Freedman, a citizen of the United States of America, residing in New York city, county of Kings, and State of New York, have invented a new, original, and ornamental Design for a Suit, of which the following is a specification, reference being had to the accompanying drawing, forming part thereof, wherein,

I claim:

The ornamental design for a suit, substantially as shown.

JULES FREEDMAN.
